Robert M. De Tray, Independence, Mo.

Application September 13, 1948, Serial No. 148,565

Term of patent 3½ years

(Cl. D14—18)

To all whom it may concern:

Be it known that I, Robert M. De Tray, a citizen of the United States, residing at 412 West Van Horn Road, Independence, in the county of Jackson and State of Missouri, have invented a new, original, and ornamental Design for an Automobile Radiator Ornament, of which the following is a specification, reference being had to the accompanying drawing, forming a part thereof.

Figure 1 is a side elevational view of an automobile radiator ornament, showing my new design.

Fig. 2 is a top plan view thereof; and

Fig. 3 is a front elevational view thereof.

I claim:

The ornamental design for an automobile radiator ornament, as shown.

ROBERT M. DE TRAY.
